UNITED STATES PATENT OFFICE.

LOUIS JUSTEMENT, OF WASHINGTON, DISTRICT OF COLUMBIA.

APARTMENT HOUSE.

Application filed April 2, 1926. Serial No. 99,313.

This invention relates to building construction, more particularly to an apartment layout for a city block as a unit; and one object of the invention is the utilization of the entire street frontage on all sides, with the exception of a garage entrance when such entrance is deemed desirable.

Another object of the invention is the elimination of alleys and of service entries, refuse collection, and similar unsightly features from the rear.

Another object of the invention is the resulting utilization of space normally occupied by rear yards as an inner garden, and whenever desired, the construction of a central heated garage in place of the usual collection of assorted tin and other type garages.

With these and other objects in view, the invention consists of certain novel features of construction, as will be more fully described and particularly pointed out in the appended claims.

In the accompanying drawings:

25 Figure 1 is a ground level plan of one form of apartment layout for a normal city block, including a central garage;

30 Figure 2 is a section through one of the unit apartments, showing the relative position of the common service way;

Figure 3 is a horizontal section showing the basements of two adjoining houses on the line 3—3 of Figure 2.

It is found in planning houses for a city block, using the normal type of square layout, that requirements for alleys and service entries in cities result in a loss of from 60 to 80 feet at each corner. In addition, the cost of paving the alleys is considerable, and the use of individual service entries and similar features makes the rear view unsightly. The system herein described in detail remedies these defects and in addition effects a considerable saving over the cost of individual house construction and upkeep.

Referring to the drawings, 1 designates corner apartment houses of the usual type, with adjoining unit houses 2 constructed in the intervening space. These units are suitable for the use of a single family, and, like row houses, have individual entrances. Unlike row houses, however, they have no individual service entries, but instead communicate with a common service way 3, through doors leading into the individual basements 4; the service ways have the usual street outlets

5, these outlets 5 leading from the basements of the corner apartments 1. The houses are separated by party walls extending from the roof to the cellar, the party walls being constructed in the usual manner of either masonry or frame. The service way 3 is separated from the house cellars by a structural or curtain wall constructed in the usual manner of masonry or frame, having openings and doors as hereinafter described.

Another object of the invention is the resulting utilization of space normally occupied by rear yards as an inner garden, and whenever desired, the construction of a central heated garage in place of the usual collection of assorted tin and other type garages.

With these and other objects in view, the invention consists of certain novel features of construction, as will be more fully described and particularly pointed out in the appended claims.

In the accompanying drawings:

25 Figure 1 is a ground level plan of one form of apartment layout for a normal city block, including a central garage;

30 Figure 2 is a section through one of the unit apartments, showing the relative position of the common service way;

Figure 3 is a horizontal section showing the basements of two adjoining houses on the line 3—3 of Figure 2.

It is found in planning houses for a city block, using the normal type of square layout, that requirements for alleys and service entries in cities result in a loss of from 60 to 80 feet at each corner. In addition, the cost of paving the alleys is considerable, and the use of individual service entries and similar features makes the rear view unsightly. The system herein described in detail remedies these defects and in addition effects a considerable saving over the cost of individual house construction and upkeep.

Referring to the drawings, 1 designates corner apartment houses of the usual type, with adjoining unit houses 2 constructed in the intervening space. These units are suitable for the use of a single family, and, like row houses, have individual entrances. Unlike row houses, however, they have no individual service entries, but instead communicate with a common service way 3, through doors leading into the individual basements 4; the service ways have the usual street outlets

5, these outlets 5 leading from the basements of the corner apartments 1. The houses are separated by party walls extending from the roof to the cellar, the party walls being constructed in the usual manner of either masonry or frame. The service way 3 is separated from the house cellars by a structural or curtain wall constructed in the usual manner of masonry or frame, having openings and doors as hereinafter described.

Another object of the invention is the resulting utilization of space normally occupied by rear yards as an inner garden, and whenever desired, the construction of a central heated garage in place of the usual collection of assorted tin and other type garages.

With these and other objects in view, the invention consists of certain novel features of construction, as will be more fully described and particularly pointed out in the appended claims.

In the accompanying drawings:

25 Figure 1 is a ground level plan of one form of apartment layout for a normal city block, including a central garage;

30 Figure 2 is a section through one of the unit apartments, showing the relative position of the common service way;

Figure 3 is a horizontal section showing the basements of two adjoining houses on the line 3—3 of Figure 2.

It is found in planning houses for a city block, using the normal type of square layout, that requirements for alleys and service entries in cities result in a loss of from 60 to 80 feet at each corner. In addition, the cost of paving the alleys is considerable, and the use of individual service entries and similar features makes the rear view unsightly. The system herein described in detail remedies these defects and in addition effects a considerable saving over the cost of individual house construction and upkeep.

avoid a large proportion of accidents due to automobile traffic on city streets and alleys.

I claim as my invention:—

1. A building construction comprising a series of contiguous houses separated from each other by party walls extending from roof to foundation and provided with a common service way substantially in the plane of the basement, connecting all the houses but separated from the house cellars by a structural or curtain wall.
2. A building construction comprising a series of contiguous houses separated from each other by party walls extending from roof to foundation and provided with a common service way substantially in the plane of the basement, connecting all the houses but separated from the house cellars by a structural or curtain wall, said curtain wall having entries to the house cellars.
3. A building construction for a city block comprising corner houses, a series of contiguous houses in the intervening space between the corner houses, and separated from each other by party walls extending from roof to foundation, and a common service way substantially in the plane of the basement, connecting all the houses but separated from the house cellars by a structural or curtain wall.
4. A building construction for a city block comprising corner houses, a series of con-

tiguous houses in the intervening space between the corner houses, and separated from each other by party walls extending from roof to foundation, and a common service way substantially in the plane of the basement, connecting all the houses but separated from the house cellars by a structural or curtain wall, said curtain wall having entries to the house cellars.

5. A building construction comprising a series of contiguous houses separated from each other by party walls extending from roof to foundation and provided with a common service way substantially in the plane of the basement, connecting all the houses but separated from the house cellars by a structural or curtain wall, said service way communicating with entrances leading from the street.

6. A building construction comprising a series of contiguous houses separated from each other by party walls extending from roof to foundation and provided with a common service way substantially in the plane of the basement, connecting all the houses but separated from the house cellars by a structural or curtain wall, said curtain wall having entries to the house cellars and said service way communicating with entrances leading from the street.

In testimony whereof I affix my signature.
LOUIS JUSTEMENT.
